HYDROSTATIC PUMP

Wayne Sprecher and Cecil Ware, Houston, Tex.

Application October 12, 1943, Serial No. 505,971

4 Claims. (Cl. 103—46)

This invention relates to a hydrostatic pump specially designed for deep wells.

An object of the invention is to provide a pump of the character described wherein the pumping piston may be operated by a liquid column thus dispensing with the use of the usual sucker rod.

A further object of the invention is to provide a pump wherein there is an outer and an inner column of liquid, the latter within the tubing and the former within the casing around the tubing with an upper cylinder and an upper piston reciprocable therein and effective to transmit power through the inner column of liquid to a lower piston reciprocable in a lower cylinder and connected to a working plunger in the working cylinder of the pump.

It is to be noted that the lower piston above referred to is of greater cross sectional area than the upper piston and that therefore power will be transmitted through the inner liquid column from the upper piston to the lower, or driving, piston by means of differential pressures on pistons of different diameters.

Another object of the invention is to provide pumping equipment of the character described whereby the head of the outer column of liquid will offset the weight of the inner column of the actuating fluid when the pump is on the up, or intake, stroke.

With the above and other objects in view the invention has particular relation to certain novel features of construction, operation and arrangement of parts an example of which is given in this specification and illustrated in the accompanying drawings wherein:

Figures 1 and 2 show vertical sectional views of the upper and lower ends, respectively, of the pump showing the parts on down, or discharge, stroke.

Figures 3 and 4 show vertical sectional views, respectively, of the pump showing the parts on up, or intake, stroke.

Figure 5 shows a cross sectional view taken on the line 5—5 of Figure 4.

Figure 6 shows a cross sectional view taken on the line 6—6 of Figure 4 and

Fig. 7 shows a side view of the assembled pump partly in section.

Referring now more particularly to the drawings wherein like numerals of reference designate the same parts in each of the figures the numeral 1 designates the well casing and the numeral 2 designates the well tubing within the casing both of which extend to the ground surface.

Incorporated into the upper end of the tub-

ing there is the cylinder 3 in which the upper, or driving, piston reciprocates. This piston may be actuated by a power device such as a walking beam, crank-throw or similar equipment, at the ground surface, through the piston rod 5.

Incorporated into the tubing, near the lower end thereof, there is the lower cylinder 6 wherein the lower driven piston 7 is mounted to reciprocate. This lower piston is of greater cross sec-

10 tional area than the upper piston 4.

Screwed onto the lower end of the cylinder 6 there is a coupling 8 and within the cylinder 6 and resting on said coupling there is a coil spring 9 on which the piston 7 rests.

15 There is a surrounding tubular jacket 10 whose lower end is screwed onto the upper end of the coupling 8 and whose upper end may be welded to a bushing 11 which surrounds, and may be welded to, the tubing 2.

20 Screwed into the lower end of the coupling 8 there is the working cylinder 12 in which the working, or pumping, plunger 13 reciprocates. This plunger is connected with the piston 7 above by means of a piston rod 14 which works through 25 a stuffing box 15 in the coupling 8.

The jacket 10 may be corrugated or otherwise reinforced to withstand abnormal pressure, if it is found to be desirable. This jacket forms a fluid tight chamber 16 and a series of ducts

30 17 lead from this chamber through the coupling 8 into the upper end of the working cylinder 12; and another series of ducts 18 lead from the lower end of the cylinder 6 into the annular space 19 between the pump and the outer casing 1.

35 Screwed onto the lower end of the working cylinder 12 there is the valve body 19 having the annular inlet valve seat 20 clamped therein by the ring nut 21 and said seat is controlled by the upwardly opening ball valve 22. The valve body 19 also has the ducts 23 leading upwardly from the central chamber 24 thereof and controlled by the upwardly opening ball valves

40 25. The body 19 has side outlets as 26 through 45 which the pumped liquid enters the annular space 19.

The tubing 2 continues on down beneath the pump and is sealed with the casing 1 by means of a packer 27 of any conventional type and beneath the packer tubing is perforated forming a screen 28.

The chamber 16 may contain either air or inert gas and is of such volume that there will only be a slight change of pressure therein as the 55 plunger 13 moves from one end of its stroke

to the other. A small quantity of high grade lubricating oil as 29 is contained in the chamber 16 to assist in maintaining a proper seal between the upper portion of the plunger 13 and the wall of the cylinder 12 as well as between the rod 14 and the stuffing box 15 and to lubricate these parts effectively.

The purpose of the chamber 16 and the air or gas therein is to provide an elastic medium which permits a free movement of the plunger 13 and at the same time sealing off all head pressure from the space 19 against the upper end of the plunger 13.

The ducts 18 are provided for the entrance and exit of the liquid in the outer column in the space 19 into and from the lower cylinder 6 thus causing the liquid head to bear against the lower face of the piston 7. Any degree of equilibrium may be maintained between the columns of liquid depending upon the head pressure of the outer column; and since the operating liquid in the inner column may be of much lower specific gravity than that in the other column, or space 19, a further differential is achieved to aid in offsetting the difference in areas between the upper and lower faces of the piston 7. Thus it is clear that by adjusting the head on the liquid column in the space 19, the opposing columns may be placed in exact equilibrium if desirable.

The spring 9 is installed in the assembly to normally maintain the piston 7 and plunger 13 in their upper position during manufacturing and installation operations and also to aid in overcoming the columnar inertia. It also aids in some respect to lift the piston and plunger assembly.

With the pump installed and the parts in the position shown in Figures 3 and 4 on downward movement of the piston 4 the liquid column in the tubing 2 will transmit the power by differential pressure to the piston and plunger assembly 7, 14, 13, forcing it downwardly and compressing the spring 9 thus forcing the liquid in the cylinder 6 out through the channels 18 into the space 19 and drawing lubricant and compressed fluid from the chamber 16 to the upper part of the working cylinder 12. The well liquid to be pumped having been drawn into the lower part of the cylinder 12 through the intake valve 22 on the previous intake stroke will be forced out through the channels 23 past the valves 25 and into the space 19 where it becomes a part of the outer column, as indicated in Figure 2.

Upon upstroke, the head pressure of the outer column having been increased to an amount equal to the displacement involved, the well liquid having been suitably drawn off, at the ground surface, now acts to seek equilibrium with the actuating fluid in the tubing 2 and becomes effective immediately upon the upstroke of the piston 4. The air or gas together with the lubricant in the upper part of the cylinder 12 are returned

into the chamber 16 and liquid from the column in the space 19 passes through the ducts 18 and applies pressure to the underside of the piston 7 which piston, aided in part by the spring 9, moves upwardly thus moving the plunger 13 upwardly and drawing in another charge of liquid past the intake valve 22. The operating liquid column in the tubing 2 is returned to its original level and thus the cycle is completed.

As illustrated upon upward movement of the piston 4 the weight of the column of pumped liquid in the casing 1 will act against the lower end of the piston 7 to move said piston, and the plunger 13, upwardly and another charge of well liquid will flow into the pumping cylinder 12. It is obvious that, if desired, equipment may be provided at the ground surface for supplementing the weight of the column of pumped fluid by the application of pressure thereto, provision being made also for taking off the pumping gain upon downstroke, or power stroke, of the plunger 13 and in this case the power applied will be fully controlled in both directions.

What we claim is:

1. In pumping equipment a pumping cylinder, a pumping plunger reciprocable therein, a well tubing, a cylinder associated with the tubing and having a piston therein, a piston rod connecting the piston and plunger, a seal around said rod, a chamber for containing a compressible fluid with a duct leading therefrom into the upper end of the pumping cylinder.

2. In pumping equipment a pumping cylinder, a pumping plunger reciprocable therein, a well tubing, a cylinder associated with the tubing and having a lower end port, a piston in said cylinder above said port, a piston rod connecting the piston and plunger, a seal around said rod between said cylinders, a chamber for containing a compressible fluid and provided with a duct leading therefrom into the upper end of the pumping cylinder.

3. In pumping equipment a pumping cylinder, a pumping plunger reciprocable therein, a well tubing, a cylinder associated with the tubing and having a piston therein, a piston rod connecting the piston and plunger, a seal around said rod, a chamber for containing a compressible fluid with a duct leading therefrom into the upper end of the pumping cylinder, a compressible fluid and a liquid lubricant in said chamber movable back and forth through the duct as the plunger reciprocates.

4. In pumping equipment a pumping cylinder, a pumping plunger reciprocable therein, a well tubing, a cylinder associated with the tubing and having a piston therein, a yieldable member supporting the piston, a piston rod connecting the piston and plunger, a seal around said rod, a chamber for containing a compressible fluid with a duct leading therefrom into the upper end of the pumping cylinder.
